UNITED STATES PATENT OFFICE.

GEORGE D. REINHARDT, OF TULSA, OKLAHOMA.

LIQUID-FUEL BURNER.

Application filed May 19, 1922. Serial No. 562,109.

To all whom it may concern:

Be it known that I, GEORGE D. REINHARDT, a citizen of the United States, and resident of Tulsa, in the county of Tulsa and State of Oklahoma, have invented certain new and useful Improvements in Liquid-Fuel Burners, of which the following is a specification.

My invention relates to liquid fuel burners and particularly to those burners adapted for use in effecting the combustion of crude or other heavy oils and wherein the oil is atomized by means of steam.

In carrying my invention into practice it has been my purpose primarily to provide an improved construction of burner of this type whereby its general effectiveness is enhanced, which will enable a very fine adjustment to be effected with extended range of usefulness, irrespective of wide variation in the density of oil, which effectively atomizes the oil prior to its passage to the burner nozzle, which can be easily and quickly cleaned, and which possesses other advantages as will hereinafter appear.

I will describe my invention in the best forms known to me at present, but it will be apparent that the same is susceptible to changes in forms and proportions and to desirable additions with the exercise of only ordinary mechanical skill and without departing from the scope thereof as set forth in the appended claims.

In the drawings chosen to illustrate my invention—

Figure 1 is a side elevation of my improved burner completely assembled;

Fig. 2, a longitudinal section through the fuel atomizing casing embodied in my burner;

Fig. 3, a perspective view of the fuel mixture conveying tube associated with the atomizing casing;

Fig. 4, a perspective view of the device for removing accumulated oil from the surface of the mixture conveying tube and for assisting the atomization of the oil;

Fig. 5, a section on the line 5—5 of Fig. 2;

Fig. 6, a view similar to Fig. 2 showing a modified form of my invention;

Fig. 7, a side elevation of a fragment of my burner and including another modified form of atomizing casing;

Fig. 8, a longitudinal section of the atomizing casing shown in Fig. 7;

Fig. 9, an end view of what is shown in Fig. 8;

Fig. 10, a section on the line 10—10 of Fig. 8;

Fig. 11, a perspective view of the disk valve employed in the atomizing casing shown in Fig. 8;

Fig. 12, a longitudinal section of the nozzle employed in my improved burner; and

Fig. 13, a section on the line 13—13 of Fig. 12.

Referring to Figures 1, 2, 3, 4 and 5, my improved burner is shown as comprising an atomizing casing A and a nozzle B. The atomizing casing A comprises a cylindrical body 15 and end members 16 and 17, said end members being provided with axially aligned passages 18 and 19, respectively, for a purpose that will presently appear. The end member 17 is provided with an oil passage 20 and a steam passage 21. The outer end of the passage 20 is connected with an oil supply pipe 22 controlled by a valve 23.

The outer end of the passage 21 is connected with a steam pipe 24 controlled by a valve 25 and connected with a steam supply pipe 26.

Mounted axially within the casing B is a mixture conveying tube 27, one end of which is threaded in the passage 18 of the head 16, while the other end thereof extends entirely through the head 17 to the exterior of the casing A. I provide the tube 27 with a spirally arranged row of equidistantly spaced ports 28, said ports decreasing progressively in cross sectional area from one end of the row to the other and said ports provide the means whereby the fuel mixture may pass from the interior of the casing A to the interior of the tube 27.

I control this passage of the fuel mixture from the casing B to the interior of the tube 27 through the medium of a valve 29 which is rotatably and slidably mounted within the bore of the tube 27. This valve is provided with an L-shaped passage 30

whose long arm extends longitudinally of the valve and opens through the end thereof adjacent the head 16, while the short arm of said passage opens through the side of the valve and forms a port 31 which is adapted to be brought successively into

registration with the ports 28 as rotary and longitudinal movement is imparted to the valve 29. In order to effect the requisite rotary and longitudinal movement of the 5 valve 29 I provide the latter with a stem 32 which extends through a stuffing box 33 screwed on the adjacent end of the tube 27. This stem 32 is provided with screw threads 34 which engage corresponding threads 35 10 provided on the stuffing box. A handle 36 is mounted on the extreme outer end of the stem 32 whereby the valve 29 may be rotated as desired. The pitch of the threads 34 and 35 corresponds to the pitch of the 15 spiral arrangement of the ports 28, so that as the valve 29 is rotated in either direction through its prescribed limits by means of the handle 36, it will partake of rotary and longitudinal movement which will bring the 20 port 31 successively into registration with the ports 28 of the tube 27. As the ports 28 are spaced equidistantly it will be obvious that successive registrations of the port 31 with the ports 28 will be had by imparting 25 equal predetermined rotations to the handle 36. In the present instance the spacement between the ports 28 is such that a quarter turn of the handle 36 will move the port 31 from a position of registration with one port 30 28 to a position of registration with an adjacent port 28. By this arrangement I am able to provide an exceedingly large number of ports 28 varying successively but slightly in cross sectional area and in this manner I 35 am enabled to obtain both a very fine and wide range adjustment of the burner.

In order to remove accumulated oil from the surface of the tube 27 within the area of the ports 28 and thereby prevent such 40 ports from becoming clogged with oil, I resort to the following construction. Rotatably mounted on the tube 27 adjacent the inner end of the end member 17 of the casing B is a rotor 37 provided with blades 38 45 with which the steam and oil entering the casing through the passages 20 and 21 is adapted to impact for the purpose of actuating the rotor 37, it being noted that the passages 20 and 21 are disposed substantially 50 tangentially of the rotor so that the steam and oil will impact properly against the blades 38 to effect the necessary rotation. Also rotatably mounted on the tube 27 is a hub 39 held against longitudinal movement by a collar 40 formed on said tube. The rotor 37 and hub 39 are so spaced as to contain between them the entire area of the ports 28 and this rotor 37 and hub 39 are connected by helical blades 41, the inner 55 edges of which are adapted to wipe the adjacent outer surface of the tube 27 during rotation thereof under the influence of the rotation of the rotor 37 and thus prevent accumulation of oil in the ports 28. In addition, the device formed by the rotor 37, 60

hub 39 and blades 41 operates during its rotation to materially assist in breaking up the oil thereby effecting a more efficient atomization. It will also be observed in this connection that as both the oil and steam impact against the blades 38 of the rotor this element alone serves to materially enhance the breaking up of the oil and proper mingling of the particles of oil and steam. In order to provide for effectively cleaning of 75 the atomizing casing A I provide the latter with a cleaning outlet 42 controlled by a valve 43. By opening this valve 43, shutting off the oil supply and turning in the steam supply it will be apparent that any 80 sediment or residue in the casing B will be effectively blown out.

In the modified form of my invention shown in Fig. 6 I provide the tube 27 with a single longitudinal row of ports 44 which 85 successively decrease in cross area from one end of the row to the other. Communication between the casing A and the tube 27 through any desired port 44 is controlled by a valve 45 having a recess 46 which communicates with a port 47 adapted to be brought successively into registration with the ports 44 by sliding movement of the valve exclusively, said valve being held against rotation by means of a pin 48 mounted in the tube 27 and engaging in a longitudinal slot 49 formed in the valve. The closed end of the valve 45 has threaded therein a screw member 50 which is held against longitudinal movement by a stuffing box construction 51 mounted on the adjacent end of the tube 27. By this construction it will be apparent that as the screw member 50 is rotated the valve 45 will be moved longitudinally to bring the port 47 successively 95 into registration with the ports 44 to effect the desired adjustment of the burner in response to the particular oil conditions at hand.

In Figures 7, 8, 9, 10 and 11 I illustrate 110 still another desirable form of atomizing casing wherein one end of the casing is closed by a threaded plug 52 which carries the mixture conveying tube 27. Secured against the inner end of the plug 52 by suitable screw 53 is a disk 54 provided with a 115 concentric row of ports 55 which decrease in cross sectional area from one end to the other. In this form of my invention steam and oil is introduced into the casing on the side of the disk 54 which is remote from the tube 27. The ports 55 are controlled by a rotatable disk valve 56 provided with a port 57 and having a stem 58 extending to the exterior of the casing and having a 120 handle 59 mounted thereon for the purpose of effecting its rotation. A spring 60 surrounds the stem 58 between one end of the casing and the valve 56 for the purpose of firmly holding said valve 56 against the disk 125 130

54. By rotating the valve 56 through the medium of the handle 59 it will be apparent that the disk 57 can be brought into successive registration with the ports 55. As convenient means for indicating the port in the disk with which the port 57 is in registration I mount on the end of the casing a suitable dial 61 and terminate one end of the handle 59 in a pointer 62. It will be observed in connection with this construction that the disk 54 is removable through the medium of the screws 53 and that in case said disk becomes worn it can be readily replaced with another.
- 15 55. In Figures 12 and 13 I have illustrated an improved form of nozzle employed in my burner, the same being indicated at B and is formed of a body suitably stepped so that its lower portion projects beyond its upper portion at its forward end. The upper portion of this nozzle is provided with a circular steam receiving chamber 63 which is connected to the steam supply pipe 26 by means of a pipe 64 controlled by a valve 65.
- 20 56. The chamber 63 is provided at the extreme bottom of the upper portion of the nozzle with a flared outlet 65 whose inner end is narrower than the diameter of the chamber 63. By this construction the steam under pressure in the chamber 63 is discharged laterally in both directions and contacts with the walls of the flared outlet 65 which in turn assist in forming the steam into a fan shaped film of relatively great extent.
- 30 57. The lower portion of the nozzle B is provided with a mixture receiving chamber 66 which is connected with the interior of the atomizing casing by means of a pipe 67. The chamber 66 is provided with an upwardly directed discharge outlet 68 opening through the surface of the step, just in advance of the outlet of the chamber 63. Thus it will be seen that the mixture discharging through the outlet 68 will be immediately intersected by the steam discharging through the outlet 65 and the flame produced by the burner will partake of the shape and the extent of the film of steam discharging from the chamber 63.
- 40 58. I claim:—
1. In a liquid fuel burner, a casing having a liquid fuel inlet, an apertured tube for conveying fuel from the casing, and rotatable means to remove accumulated deposits of fuel from the tube.
  2. In a liquid fuel burner, a casing having a liquid fuel inlet, an apertured tube extending within the casing for conveying fuel from the casing, and means within the casing and rotatable about the tube to remove accumulated deposits of fuel therefrom.
  3. In a liquid fuel burner, a casing having a liquid fuel inlet, a tube for conveying fuel from said casing, said tube being provided
54. with a plurality of longitudinally spaced ports each of which differs in cross sectional area from any of the others, and a tubular member movable longitudinally through the tube to control the flow of fuel from the casing to the tube, said member being provided with a single port for registration with a selected port in the tube.
55. 4. In a liquid fuel burner, a casing having a steam inlet and a liquid fuel inlet, a tube extending longitudinally through the casing for conveying a mixture of steam and fuel from the casing, said tube being provided with a plurality of ports, each of which differs in cross sectional area from any of the others, and a valve within the tube operable from without the casing to effect such communication between the casing and tube through a desired port and simultaneously close such communication through all of the other ports.
56. 5. In a liquid fuel burner, a casing having a steam inlet and a liquid fuel inlet, a tube for conveying a mixture of steam and fuel from the casing, said tube being provided with a plurality of ports, each of which differs in cross sectional area from any of the others, and a longitudinally slideable valve within the tube operable from without the casing to effect such communication between the casing and tube through a desired port and simultaneously close such communication through all of the other ports.
57. 6. In a liquid fuel burner, a casing having a steam inlet and a liquid fuel inlet, a tube for conveying a mixture of steam and fuel from the casing, said tube being provided with a plurality of ports, each of which differs in cross sectional area from any of the others, and a rotatable valve within the tube operable from without the casing to effect such communication between the casing and tube through a desired port and simultaneously close such communication through all of the other ports.
58. 7. In a liquid fuel burner, a casing having a steam inlet and a liquid fuel inlet, a tube for conveying a mixture of steam and fuel from the casing, said tube being provided with a plurality of ports, each of which differs in cross sectional area from any of the others, and a rotatable and longitudinally slideable valve within the tube operable from without the casing to effect such communication between the casing and tube through a desired port and simultaneously close such communication through all of the other ports.
59. 8. In a liquid fuel burner, a casing having a steam inlet and a liquid fuel inlet, a tube extending longitudinally through the casing for conveying a mixture of steam and fuel from the casing, said tube being provided with a plurality of ports, each of which

which differs in cross sectional area from any of the others, a movable valve within the tube for effecting communication between the casing and the tube through a desired 5 port and simultaneously close said communication through all of the other ports, and nut and screw means for moving said valve.

9. In a liquid fuel burner, a casing having a steam inlet and a liquid fuel inlet, a tube 10 for conveying a mixture of steam and fuel from the casing, said tube being provided with a plurality of ports, each of which differs in cross sectional area from any of the others, a longitudinally slidable valve with- 15 in the tube for effecting communication between the casing and tube through a desired port and simultaneously close said communication through all of the other ports, and nut and screw means for sliding the 20 valve.

10. In a liquid fuel burner, a casing having a steam inlet and a liquid fuel inlet, a tube for conveying a mixture of steam and fuel from the casing, said tube being 25 provided with a plurality of ports, each of which differs in cross sectional area from any of the others, a rotatable and longitudinally slidable valve within the tube for effecting communication between the casing and tube through a desired port and simultaneously close such communication through all of the other ports, and nut and screw means for rotating and longitudinally moving said valve.

35 11. In a liquid fuel burner, a casing having a steam inlet and a liquid fuel inlet, a tube extending longitudinally through the casing for conveying a mixture of steam and fuel from the casing, said tube being 40 provided with a spirally arranged row of equidistantly spaced ports progressively decreasing in cross sectional area from one end of the row to the other, a rotatable and longitudinally slidable valve for effecting 45 communication between the casing and tube through a desired port and simultaneously close such communication through all of the other ports, and rotatable means for imparting rotary and longitudinal movements to the valve, said means being adapted upon predetermined equal amounts of rotation to close a previously open port and open an adjacent port.

55 12. In a liquid fuel burner, a casing having a steam inlet and a liquid fuel inlet, a tube extending longitudinally through the casing for conveying a mixture of steam and fuel from the casing, said tube being 60 provided with a spirally arranged row of equidistantly spaced ports progressively decreasing in cross sectional area from one end of the row to the other, a rotatable and longitudinally slidable valve for effecting 65 communication between the casing and tube to a desired port and simultaneously close

such communication through all of the other ports, and screw means for imparting rotary and longitudinal movements to the valve, said means being adapted upon equal and predetermined amounts of rotation to close 70 a previously open port and open an adjacent port.

13. In a liquid fuel burner, a casing having a steam inlet and a liquid fuel inlet, a tube extending longitudinally through the 75 casing for conveying a mixture of steam and fuel from the casing, said tube being provided with a spirally arranged row of equidistantly spaced ports progressively decreasing in cross sectional area from one end of the row to the other, a rotatable and longitudinally slidable valve for effecting communication between the casing and tube through a desired port and simultaneously close such communication through all of the 80 other ports, and means for imparting rotary and longitudinal movements to the valve, said means being adapted upon predetermined equal amounts of movement to close a previously open port and open an 85 adjacent port.

14. In a liquid fuel burner, a casing having a steam inlet and a liquid fuel inlet, a tube extending longitudinally through the 90 casing for conveying a mixture of steam and fuel from the casing, said tube being provided with a spirally arranged row of equidistantly spaced ports progressively decreasing in cross sectional area from one end of the row to the other, a rotatable and longitudinally slidable valve in said tube for effecting communication between the casing and tube through a desired port and simultaneously close such communication through all of the other ports, and rotatable means for imparting rotary and longitudinal movements to the valve, said means being adapted upon equal predetermined amounts of rotation to close a previously open port and open an adjacent port. 100

15. In a liquid fuel burner, a casing having a steam inlet and a liquid fuel inlet, a tube extending longitudinally through the 105 casing for conveying a mixture of steam and fuel from the casing, said tube being provided with a spirally arranged row of equidistantly spaced ports progressively decreasing in cross sectional area from one end of the row to the other, a rotatable and longitudinally slidable valve in said tube for effecting communication between the casing and tube through a desired port and simultaneously close such communication through all of the other ports, and screw means for imparting rotary and longitudinal movements to the valve, said means being adapted upon equal predetermined amounts of rotation to close a previously open port and open an adjacent port. 115

16. In a liquid fuel burner, a casing hav- 120

ing a steam inlet and a liquid fuel inlet, a tube extending longitudinally through the casing for conveying a mixture of steam and fuel from the casing, said tube being provided with a spirally arranged row of equidistantly spaced ports progressively decreasing in cross sectional area from one end of the row to the other, a rotatable and longitudinally slid able valve in said tube for effecting communication between the casing and tube through a desired port and simultaneously close such communication through all of the other ports, and movable means for imparting rotary and longitudinal movements to the valve, said means being adapted upon equal predetermined amounts of movement to close a previously open port and open an adjacent port.

17. In a liquid fuel burner, a casing having a steam inlet and a liquid fuel inlet, a tube for conveying a mixture of steam and fuel from the casing, said tube being provided with a plurality of ports, each of which differs in cross sectional area from any of the others, means within the tube for effecting such communication between the casing and tube through a desired port and simultaneously close such communication through all of the other ports, and means operated by incoming steam to remove accumulated material from the outer surface of the tube.

18. In a liquid fuel burner, a casing having a steam inlet and a liquid fuel inlet, a tube for conveying a mixture of steam and fuel from the casing, said tube being provided with a plurality of ports, each of which differs in cross sectional area from any of the others, means within the tube for effecting such communication between the casing and tube through a desired port and simultaneously close such communication through all of the other ports, and means operated by incoming steam to remove accumulated material from the outer surface of the tube over the entire area of said ports.

19. In a liquid fuel burner, a casing having a steam inlet and a liquid fuel inlet, a tube for conveying a mixture of steam and fuel from the casing, said tube being provided with a plurality of ports each of which

differs in cross sectional area from any of the others, means within the tube for effecting such communication between the casing and tube through a desired port and simultaneously close such communication through all of the other ports, and means for removing accumulated material from the outer surface of the tube over the entire area of said ports, said means comprising a bladed rotor mounted on the tube and against the blades of which the incoming steam and oil impact to actuate said rotor, a hub rotatably mounted on the tube and spaced from the rotor, said rotor and hub confining between them the ports in the tube, and spiral blades connecting the hub and rotor and adapted to remove accumulated material over the port area as they are rotated under the influence of said rotor.

20. In a liquid fuel burner, a casing having a steam inlet and a liquid fuel inlet, a tube for conveying a mixture of steam and fuel from the casing, said tube being provided with a plurality of ports each of which differs in cross sectional area from any of the others, means within the tube for effecting such communication between the casing and tube through a desired port and simultaneously close such communication through all of the other ports, and a bladed rotor mounted on the tube and actuated by the impact of incoming steam and fuel against its blades.

21. A nozzle for liquid fuel burners comprising a body having a stepped forward end to dispose its bottom portion in advance of its upper portion, said upper portion of the body having a circular steam receiving chamber provided with an outwardly flared discharge mouth whose width at its inner end is less than the diameter of the chamber, said mouth being positioned to discharge across the surface of the step and said lower portion of the body having a fuel receiving chamber provided with an outlet directed upwardly through the surface of the step so as to be intersected by the discharge from the steam chamber.

In testimony whereof I hereunto affix my signature.

GEORGE D. REINHARDT.
